Primary Examiner — Robert Delehaney(74) *Attorney, Agent, or Firm* — Foley & Lardner LLP**(57) CLAIM**

I claim the ornamental design for a sprayhead for faucet, as shown and described.

DESCRIPTION

FIG. 1 is a top, rear, right perspective view of an embodiment of the claimed design;

FIG. 2 is a right elevation view thereof;

FIG. 3 is a left elevation view thereof;

FIG. 4 is a front elevation view thereof;

FIG. 5 is a rear elevation view thereof;

FIG. 6 is a top plan view thereof; and,

FIG. 7 is a bottom plan view thereof.

The ornamental design which is claimed is shown in solid lines in the drawings. The broken lines in the drawings form no part of the claimed design. Broken lines formed by equal length dashes show unclaimed subject matter.
